LINOTYPE AND INTERTYPE MAGAZINE
STORAGE CABINET AND A RAIL UNIT
PROVIDED THEREIN

Archie B. Reid, Chicago, Ill.

Application May 14, 1934, Serial No. 725,497

4 Claims. (Cl. 276—44)

My invention relates in general to storage racks, and more in particular to a removable rail unit for a rack to store matrices for type casting machines.

At the present time matrices for type-casting machines, or type magazines as they are called, are stored in racks having a plurality of steel channels, with each channel designed for receiving a magazine. The magazines are very heavy, and because of this weight are not ordinarily handled with the greatest amount of care. They are pushed into the rack by the operator and slide on one side, or an open face, along the bottom of the steel channel. In some racks steel rollers are spaced apart along the bottom of the channel to carry the magazines. In either type of rack, it is a matter of the metal magazine being pushed over the steel channel surface or steel roller. Considerable wear occurs on the magazines, and actual injury often results, particularly to the open faced magazine when pushed into the rack.

The magazines are expensive, and the cost of repair or replacement due to wear or injury from the present storage facilities amounts to a considerable sum. The same amount of wear also occurs on the rack, and with the present construction failure of one of the channels necessitates replacement of the entire cabinet.

It is an object of my invention to provide an improved storage rack for type magazines.

A further object is to provide a magazine receiving rail for a storage cabinet, which will cause neither wear nor injury to the side or face of the magazine as it is pushed in and pulled out of the cabinet.

A still further object is to provide a replaceable individual rail for the storage cabinet, for receiving a magazine, and

It is also an object of my invention to provide such a device, which is simple, sturdy, and inexpensive to manufacture.

Other objects and advantages of my invention will be apparent from the following description taken with the drawing in which:

Fig. 1 is a perspective of a storage cabinet with the individual rail units assembled therein, and carrying a magazine.

Fig. 2 is a perspective view of the individual rail unit, and

Fig. 3 is a sectional view along the line 3—3 of Fig. 2.

Fig. 4 is a perspective view of a standard type of magazine.

In practicing my invention I provide a rail

unit for mounting in a storage cabinet for type magazines, with said unit including a channel member, a plurality of rollers individually mounted in an adjoining position in the channel, and a continuous belt movable over the rollers to receive a type magazine and carry the same into the storage cabinet.

Referring now to the drawing, a rail 10 is provided for removable mounting in a storage cabinet 10^a as shown in Fig. 1. The rail comprises a pair of L-shaped members 11 and 12 adapted to fit together in an overlapping relationship with bottom portion 13 of member 11 carrying the base 14 of member 12. An ear 16 extends outwardly from each end of the base portion 13 and 14 of the respective L-shaped members, with corresponding ears having corresponding apertures 17 therein. The individual rails 10 are mounted adjacent one another as shown in Fig. 1, with bolts 18 extending through the aperture 17 and through angleirons 19 or a similar structure in the cabinet 11.

The L-shaped side members give a rigid construction to the entire rail unit, and inasmuch as they may be stamped out with an inexpensive die, at a low labor cost, this construction assists in maintaining a low manufacturing cost for the entire unit. Furthermore, the overlapping assembly with the double thickness for the bottom strengthens the rail for carrying the relatively large weight of a magazine. However, it is understood that a single piece channelled member may also be employed.

As discussed above, the ordinary type magazine 21 as shown in perspective in Fig. 4 and mounted in the storage cabinet in Fig. 1, is itself very heavy, and when carrying the usual amount of type comprises an exceptionally heavy device for ordinary handling. The magazine is ordinarily lifted from the type casting machine and pushed into the storage cabinet on the open face 22. Some types of magazines also are pushed into the cabinet on a covered edge. In any event, whether slid into the cabinet upon an open face or a covered edge, considerable wear takes place on this portion of the magazine. To overcome this difficulty in my invention I provide a series of rollers 23 rotatably mounted adjacent one another over the length of the rail 10, and having a continuous belt 24 for carrying a type magazine extending around the outside rollers 23 and resting on the intermediate rollers as shown by the dotted lines in Fig. 2.

The rollers 23 are individually mounted on a stud 25 carried in the sides of the members 11 and 12, in a position such that a portion A of the side walls extends above the belt surface to form a guide wall for the rail passage. Inasmuch as there is no contact of the magazine directly with the roller 23, satisfactory results have been obtained with the use of a wooden roller, although it is understood, of course, that any material may be employed. With the use of a wooden roller the cost is reduced as contrasted with a steel roller for instance, and the weight of the entire unit is materially less than would be the case with the metal construction. The stud 25 may consist of a headed bolt with a nut 26 threaded upon one end thereof. The roller itself is rotatably carried on a spacing sleeve 27 around the body of the bolt 25, adapted to properly space the walls of the members 11 and 12. The bolts 25 carry the spacers 27 and act to rigidly secure the L-shaped members in overlapping position.

In the use of my rail in a storage cabinet, the magazine 21 is inserted in the ordinary manner and as the forward end of the same engages the belt 24 it is frictionally retained in position on the belt and maintains this position as the belt is carried over the rollers 23. In other words after the magazine initially touches the belt there is no further sliding movement as between the two. In this manner there is no possibility of injury to the open face or straight edge of the magazine on the somewhat soft, yielding surface provided by the belt. The rollers 23 are close enough together so that with the magazine riding on the belt there is no bumping action of the same as said magazine is carried into the cabinet. Guideways 29 are provided on the top of the cabinet for receiving the top of the magazine.

Although it has been found that comparatively little wear occurs on the movable belt 24 because of the fact that there is no sliding movement between the magazine and belt, it sometimes happens that it is necessary to remove a unit for replacement or repair. This removal is readily accomplished by simply taking out the bolts 18 at each end of the rail, thus obviating the necessity of replacing an entire cabinet upon excessive wear of any of its parts.

In the event that the belt stretches with use, I provide an adjustment for tightening the same by forcing the rear roller 23 backwardly in the

elongated bearing slots 30 in each of the side walls. After the desired adjustment is secured, the rear roller is retained in position by tightening the nut 26 on the stud 25 until the spacer 27 is in rigid frictional engagement with the inside of the vertical walls. The roller may then rotate on the spacer in the usual manner.

Although I have described my invention in its preferred embodiment, it is understood that I do not limit myself thereby, but limit the invention only by the scope of the appended claims.

I claim:

1. In a storage cabinet for type magazines, a plurality of removable rail units, each comprising a channelled body member having a continuous movable belt extending substantially the length thereof to receive a type magazine and carry it in frictional engagement therewith into the storage cabinet, and means for removably mounting each of said rail units in said storage cabinet.

2. A rail unit for a type magazine storage cabinet including a pair of L-shaped members having overlapping flanges to provide a channelled passageway, a plurality of rollers mounted over the length of said passageway, a plurality of bolts extending through the side walls of the channel across the passageway to hold the L-shaped members in overlapping relationship, and each carrying a roller axis, and a belt movable over the rollers to receive a magazine and carry it into the cabinet.

3. A rail unit for mounting in a type magazine storage cabinet, said unit including a pair of L-shaped elongated members, each having a base portion and a side portion, with said base portions overlapping, and the side portions oppositely disposed to provide an elongated channelled passageway, a plurality of rollers in said passageway, an axis for each roller journaled in the side portions, and a continuous movable belt carried on the rollers.

4. In an upright cabinet, a compartment for storage of type magazines, a plurality of rail units removably mounted on the bottom of the compartment, said units each comprising a channelled body member, a plurality of rollers each rotatably supported on an axis journaled in the side walls of the body member, a continuous movable belt on said rollers to carry a type magazine into said compartment, and the channelled guideways in the top of the compartment corresponding with said rail units.
